(57) **ABSTRACT**

A chronograph mechanism includes an energy accumulator, a regulating system, and a gear train connecting the energy accumulator to the regulating system. The energy accumulator is formed by a strip-spring and includes a device for driving the gear train arranged to regulate the torque delivered by the strip-spring.

CHRONOGRAPH MECHANISM

CROSS REFERENCE TO RELATED APPLICATIONS

This is a Continuation Patent Application of non-provisional patent application Ser. No. 15/044,411 filed on Feb. 16, 2016, which claims benefit of priority from European Patent Application No. 15156070.3 filed on Feb. 23, 2015, the entire disclosure of which is incorporated herein by reference and priority is claimed thereto.

FIELD OF THE INVENTION

The invention relates to the field of mechanical horology. It more specifically concerns an autonomous chronograph mechanism comprising its own energy accumulator, its own regulating system, and a gear train connecting the energy accumulator to the regulating system. The present invention also concerns a timepiece including such a chronograph mechanism.

BACKGROUND OF THE INVENTION

Chronograph mechanisms can be classified in two categories:

chronograph mechanisms implemented in connection with the going train of a timepiece
independent chronograph mechanisms, with their own going train, located in a timepiece comprising its own basic time movement.

As regards the independent chronograph mechanism category, the energy can be supplied by an additional barrel or another resilient means able to accumulate an amount of energy and redistribute it as the most constant torque possible.

However, the use of an additional barrel requires the designer to provide a dual movement, for the time and the chronograph. This dual movement generally causes a congestion problem requiring very large parts to be provided to accommodate the dual movement, which is unattractive.

SUMMARY OF THE INVENTION

It is an object to overcome the various drawbacks of known timepieces comprising an independent or autonomous chronograph mechanism.

More specifically, it is an object of the invention to provide a chronograph mechanism that is more compact.

More specifically, it is an object of the invention to provide a chronograph mechanism comprising an energy accumulator that is more compact.

It is another object of the invention to provide a chronograph mechanism comprising an energy accumulator able to deliver the most constant torque possible.

It is another object of the invention to provide a chronograph mechanism comprising an energy accumulator able to regulate the delivered torque.

To this end, the present invention concerns an autonomous chronograph mechanism comprising its own energy accumulator, its own regulating system, and a gear train connecting the energy accumulator to the regulating system.

According to the invention, said energy accumulator is formed by a strip-spring.

Thus, the energy accumulator occupies less space than conventionally used energy accumulators, which makes it

2

possible to design timepieces comprising autonomous chronograph mechanisms of smaller volume.

Preferably, the chronograph mechanism can comprise means for driving the gear train arranged to regulate the torque delivered by the strip-spring.

According to a particularly preferred variant embodiment, the gear train drive means may comprise a rack having one end arranged to cooperate with the strip-spring and another end arranged to cooperate with the gear train, wherein said rack is mounted to pivot in one direction of rotation to drive the gear train.

Advantageously, the gear train may comprise a minute counter including a first toothed sector and the rack may have a toothing arranged to cooperate with said first toothed sector, and the first toothed sector of the minute counter and the rack toothing are not concentric.

The non-concentric toothing/toothed sector system can advantageously correct the non-constant defect of the torque delivered by the strip-spring.

Preferably, the rack may also be mounted to pivot in the opposite direction of rotation in order to reset the minute counter to zero and to wind the strip-spring at the same time.

Advantageously, the chronograph mechanism may comprise a device for regulating the torque delivered by the strip-spring.

Advantageously, the torque regulating device may comprise an adjustable eccentric.

Preferably, the chronograph mechanism may comprise a mechanism for winding the energy accumulator and resetting the minutes to zero, arranged to wind the energy accumulator and reset the minutes to zero at the same time.

Advantageously, the chronograph mechanism may comprise a mechanism for starting the counting, arranged to release the regulating system when the counting starts.

The present invention also concerns a timepiece including a chronograph mechanism as defined above.

BRIEF DESCRIPTION OF THE DRAWINGS

Other characteristics and advantages of the invention will appear more clearly upon reading the following description of a specific embodiment of the invention, given simply by way of illustrative and non-limiting example, and the annexed Figures, among which:

FIG. 1 is a perspective view of the chronograph mechanism according to the invention before it is first started.

FIG. 2 is a bottom view (back cover side) of the chronograph mechanism according to the invention and of the strip-spring winding and zero reset mechanism.

FIG. 3 is a top view (dial side) of the strip-spring and of the torque regulating means in the rest position.

FIG. 4 is a top view (dial side) of the strip-spring and of the torque regulating means in the wound position.

FIG. 5 is a bottom view (back cover side) of the chronograph mechanism according to the invention and its mechanism for starting the counting.

FIG. 6 is a bottom view (back cover side) of the chronograph mechanism according to the invention and its stop mechanism.

FIG. 7 is a sectional view of the uncoupling device.

DETAILED DESCRIPTION OF THE INVENTION

Referring to FIG. 1, the chronograph mechanism comprises an energy accumulator 1, a going train 2, an escapement system 3 and a regulating system 4 comprising a

balance **4a** and a balance spring **4b**, said going train **2** connecting energy accumulator **1** to escapement system **3** and to regulating system **4**. Thus, the chronograph mechanism comprising its own chronograph movement is autonomous or independent and can be used in a timepiece comprising its own horological movement.

According to the invention, the energy accumulator is formed by a strip-spring fixed on the frame at A.

The going train comprises a minute-counter and a seconds-counter so as to also form a chronograph counter train. The going train or chronograph counter train is referred to generally hereafter as the "gear train". More specifically, the gear train comprises a minute-counter **5** and a seconds-counter **6**. Minute-counter **5** comprises a minute-wheel set comprising a first toothed sector **7** arranged to cooperate with the energy accumulator, as will be described in detail below, and a second toothed sector **8** arranged to cooperate with the gear train. The first and second toothed sectors **7, 8** are permanently fixedly mounted on arbor **10** of minute-counter **5** so that they are constantly integral in rotation, including with arbor **10**. There is no friction connection which could angularly uncouple arbor **10** from one of toothed sectors **7, 8** beyond a certain torque. Arbor **10** integrally carries a first minute indicator member (not shown), such as a hand, arranged to appear on the dial side. A second minute indicator member **12**, such as an index, is carried by second toothed sector **8** to appear on the back cover side. Seconds-counter **6** comprises a seconds-wheel set comprising a seconds pinion **14** arranged to cooperate with minute-counter **5** and a seconds wheel **16** arranged to cooperate with regulating system **4**. Arbor **18** of the seconds-wheel set integrally carries a seconds indicator member (not shown), such as a hand. There is a friction connection between the seconds-wheel set and its arbor **18** to allow for an independent angular motion of these two members beyond a certain torque.

The chronograph mechanism also comprises a zero-reset mechanism comprising a mechanism for resetting the minutes to zero and a mechanism for resetting the seconds to zero. The seconds zero-reset mechanism is a conventional reset mechanism implementing a system with a heart-piece **20** integral with arbor **18** of the seconds-wheel set, and a hammer (not shown) controlled by a reset push-piece **22** (cf. FIG. 2).

The minute-zero reset mechanism comprises a rack **24** having one end **24a** arranged to cooperate with energy accumulator **1**, as will be described hereafter, and another end **24b** having a toothing arranged to cooperate with first toothed sector **7** of the minute-wheel set. Rack **24** is mounted to pivot on the frame at B, and is arranged to pivot in one direction to ensure the minute zero-reset and energy accumulator winding functions, and to pivot in the other direction to ensure the function of driving the gear train, and, more specifically, the minute-counter during counting, when the chronograph mechanism is in operation. Thus, rack **24** forms not only the gear train drive means and the minute zero-reset mechanism but also the mechanism for winding strip-spring **1**.

To ensure its function as the gear train drive means, end **24a** of rack **24** is arranged to be actuated by the free end **1a** of strip-spring **1** and to pivot rack **24** when strip-spring **1** releases its energy and relaxes to return to a non-wound position.

In order to regulate the torque delivered by the strip-spring, the toothings provided at end **24b** of rack **24** and first toothed sector **7** of minute counter **5** are not concentric. The use of a non-concentric gear system makes it possible to

correct the non-constant torque delivered by the strip-spring and consequently to smooth the torque so that the chronograph achieves a constant amplitude and rate.

In order to regulate the torque delivered by the strip-spring, the chronograph mechanism comprises a torque regulating device. Referring to FIGS. 3 and 4, this torque regulating device comprises an eccentric cam **26**, which can be adjusted by the manufacturer by means of a key. Cam **26** is disposed in proximity to end **1b** of strip-spring **1**, beyond point A, opposite the free end **1a**. During the assembly of strip-spring **1**, cam **26** is disposed so that it is not in contact with end **1b**, as shown in FIG. 3. In order to regulate the torque to be delivered, cam **26** is rotated in the direction of arrow **a** as shown in FIG. 4, so that it is in contact with end **1b** of strip-spring **1** and in order to pivot end **1B** more or less about point A in the direction of arrow **b** to adjust the tension of strip-spring **1** in its wound position. The assembly is then secured by means of screws.

The chronograph mechanism is kept stopped until it is started by means of a mechanism for starting the counting, arranged to release the regulating system when counting starts. Referring to FIG. 5, the counting start mechanism comprises a first lever **28** controlled by a "start" push-button **30** and provided with a jumper spring **31**. First lever **28** controls a second lever **32** mounted to pivot at C on the frame and carrying a balance stop lever **34** whose free end **34a** comprises a beak arranged to cooperate with the balance wheel and lock it until the chronograph mechanism is started. Second lever **32** also carries an index **36** which pivots to indicate the state of chronograph.

To be able to perform the minute zero-reset function and the function of winding strip-spring **1** of rack **24** at the same time, the minute zero-reset and strip-spring winding mechanism comprises, referring to FIG. 2, a lever **40** actuated by zero-reset push-button **22**. Lever **40** comprises a beak **40a** which cooperates with the end **42a** of a first lever **42**, the other end cooperating with a second lever **44**. This second lever **44** comprises an arm **44a** arranged to press on end **24a** of rack **24** and to pivot rack **24** at B. During the pivoting, end **24a** of rack **24** presses on strip-spring **1** to move and wind the strip-spring while the other end **24b** of rack **24** causes first toothed sector **7** to pivot in the resetting direction of minute-counter **5**. Thus, strip-spring **1** is rewound by means of the minute-counter **5** reset function. No other specific winding action is required.

To ensure the chronograph mechanism stop function, there is provided a stop mechanism arranged to stop balance **4a** and the chronograph mechanism indicator members to allow for reading or for a timeout. To this end, zero-reset button **22** is also a chronograph mechanism stop button. Referring to FIG. 6, lever **40** controlled by button **22** also cooperates with lever **32** via a pin **43** which is integral with said lever **32** and moves in an oblong hole **45** provided in a lever **41**. The pivoting of lever **40** causes lever **32** to pivot so as to return stop balance lever **34** to a position in which balance **4a** is locked and to stop the chronograph mechanism, with no zero-reset.

Lever **41** comprises a nose-portion **41a** arranged to cooperate with lever **42** and to keep its end **42a** away from beak **40a** of lever **40** when the zero-reset function is not actuated. The pivoting of lever **32** causes pin **43** to move and pivot lever **41**. The configuration is arranged such that, at the end of the chronograph stop function, lever **41** has turned sufficiently to release lever **42**, which then falls on lever **40** so that the end **42a** of lever **42** and beak **48** of lever **40** are locked.

Thus, a first application of pressure on push-button 22 stops the chronograph mechanism and a second application of pressure on the same push-button 22 resets the counters to zero and rewinds the strip-spring.

In order to isolate the seconds wheel set when minute-counter 5 is reset to zero, the gear train comprises an uncoupling device between minute-counter 5 and seconds-counter 6, arranged to kinematically connect the minute-wheel set and the seconds-wheel set during counting, when the chronograph mechanism is operating, and to uncouple the seconds-wheel set from the minutes-wheel set when the minutes are reset to zero. This uncoupling device comprises a unidirectional mechanism having a drive direction of rotation for driving seconds-counter 6 via minutes-counter 5 during counting and a free direction of rotation when the chronograph mechanism is reset to zero. According to a variant embodiment that is not shown, this unidirectional mechanism may be a ratchet wheel.

According to another embodiment more particularly shown with reference to FIGS. 1, 5, and 7, the uncoupling device comprises a drive wheel set, comprising a drive pinion 46 cooperating with second toothed sector 8 of minute-counter 5 and a drive wheel 48, and a planetary wheel holder 50 arranged coaxially to the drive wheel arbor 52 and movably mounted to rotate about said arbor 52. Planetary wheel holder 50 cooperates with seconds pinion 14 of seconds-counter 6. Said planetary wheel holder 50 carries five, regularly distributed planetary wheels 54, mounted for free rotation. Planetary wheels 54 are arranged to cooperate with drive wheel 48 of the drive wheel set.

Planetary wheels 54 have a unidirectional tooth profile and an asymmetrical tooth profile arranged to lock with drive wheel 48 when it turns in one direction during counting, and to rotate freely when drive wheel 48 turns in the opposite direction when the minutes are reset to zero and strip-spring 1 is wound.

Thus, planetary wheels 54 make it possible to drive planetary wheel holder 50 via the drive wheel during counting, so as to drive the gear train via minute-counter 5 as far as regulating system 4 during counting, and let said planetary wheel holder 50 rotate freely when the minutes are reset to zero and strip-spring 1 is wound, so as to uncouple the seconds-wheel set from the minute-wheel set, thereby forming another variant of the unidirectional mechanism. Such an uncoupling device may be used with any type of energy accumulator and drive means, independently of the strip-spring/rack system. In particular, it could advantageously be used for winding a movement with a fusee.

The chronograph mechanism according to the invention operates as follows.

The energy required for operation of the chronograph is provided by the user when the chronograph is reset to zero, and more specifically when the minutes are reset to zero which occurs at the same time that strip-spring 1 is wound. To achieve this, the user presses the zero-reset and winding button 22. As shown in FIG. 2, pressure on button 22 in the direction of arrow a causes lever 40 to pivot in the direction of arrow b, which causes first lever 42 to move in the direction of arrow c, which causes second lever 44 and its arm 44a to tip in the direction of arrow d. As it tips, arm 44a presses on end 24a of rack 24 in the direction of arrow e, which causes the rack to pivot at B. The pivoting of the rack at B firstly causes strip-spring 1 to pivot at A, thereby winding the latter, as a result of end 24a of rack 24 pressing on free end 1a of strip-spring 1 and also causes first toothed sector 7 of minute-counter 5 to pivot, driven by toothing 24b in the direction of arrow f. Since second toothed sector 8 and

minute-counter arbor 10 are integral with first sector 7, they are driven by the same angle and reset to zero the minute indicator members, and particularly index 12. During its rotation, second toothed sector 8 of minute-counter 5 meshes with drive wheel 46, 48, but owing to the asymmetrical tooth profile of planetary wheels 54, the rotation of drive wheel 48 has no effect on planetary wheels 54, or on planetary wheel holder 50, which rotates freely. The seconds-wheel set and the rest of the gear train are therefore isolated by means of this uncoupling device while the minutes are reset to zero.

When zero-reset and winding button 22 is pressed, the seconds-counter is also reset to zero in a known manner.

During this zero reset and winding step, the energy required for operation of the chronograph is stored in strip-spring 1, which works in flexion.

The user then starts the counting by pressing the "start" button 30. As shown in FIG. 5, this causes lever 28 to tip in the direction of arrow a, which causes lever 32 to tip in the direction of arrow b, such that the end 34a of balance stop lever 34 is freed from the balance to release regulating system 4. The counting can then start. Energy is released by the strip spring whose end 1a presses on end 24a of rack 24 and pivots it at B in the opposite direction to the minute zero-reset and winding direction. As it pivots, toothing 24b drives first toothed sector 7 and thus second toothed sector 8 in the opposite direction to the minute zero-reset and winding direction. The minute indicator members start to turn at a rate of one graduation per minute. In this configuration, the second toothed sector 8 of minute-counter 5 meshes with drive wheel 46, 48, but owing to the asymmetrical tooth profile of planetary wheels 54, said planetary wheels 54 are locked so that the rotation of drive wheel 48 causes planetary wheel holder 50 to rotate, which in turn causes seconds-counter 6 to transmit the torque delivered by the strip-spring to the other gear train elements. The seconds indicator member starts to turn to indicate the seconds.

The balance and the indicator members can be stopped by a first press on push button 22 for a reading or for a timeout. As shown in FIG. 6, a first press on button 22 in the direction of arrow a causes lever 42 to pivot in the direction of arrow b, which causes levers 32 and 41 to move in the direction of arrow c to return balance stop lever 34 against balance 4a in order to lock it. The indicator members are stopped for an intermediate reading or a timeout. Lever 41 has also pivoted in the direction of arrow d to release lever 42, which falls on lever 40 to occupy its position for a zero-reset. Another press on the "start" button 30 restarts the chronograph mechanism, as described above, with no zero-reset. Another first press on button 22 stops the chronograph mechanism, as described above. A second press on button 22 resets the chronograph to zero, and rewinds the strip spring as already described above.

The chronograph mechanism according to the invention has sufficient constant torque to operate properly and is more compact than known chronograph mechanisms. The zero reset mechanism, and more specifically the minute-zero reset mechanism, also performs the function of winding the energy accumulator, so that no specific winding mechanism is required.

What is claimed is:

1. A chronograph mechanism comprising:
an energy accumulator comprised of a strip-spring;
a regulating system;
a gear train;

a mechanism for winding the energy accumulator and resetting a minute counter to zero, arranged to wind the energy accumulator and reset the minute counter to zero at a same time; and
 a rack;
 wherein the rack has one end arranged to directly engage the strip-spring and another end arranged to directly engage with the gear train,
 wherein the rack is arranged to regulate a torque delivered by the strip-spring,
 wherein the rack is mounted to pivot in one direction of rotation to drive the gear train,
 wherein the rack connects the energy accumulator directly to the regulating system through the gear train driven by the rack, and
 wherein the mechanism for winding the energy accumulator and resetting a minute counter to zero includes at least one lever arranged to directly engage the one end of the rack.

2. The chronograph mechanism according to claim 1, wherein the gear train comprises a minute-counter including a first toothed sector,
 wherein the rack has a toothing arranged to cooperate with the first toothed sector, and
 wherein the first toothed sector of the minute-counter and the rack toothing are not concentric.

3. The chronograph mechanism according to claim 2, wherein the rack is also mounted to pivot in an opposite direction of rotation to reset the minute-counter to zero and to wind the strip-spring at a same time.

4. The chronograph mechanism according to claim 1, the chronograph mechanism further comprising an adjustable

eccentric cam, wherein the adjustable eccentric cam is disposed to one end of the strip-spring, opposite to another end of the strip-spring cooperating with the rack.

5. The chronograph mechanism according to claim 1, the chronograph mechanism further comprising a mechanism for starting a counting, arranged to release the regulating system when the counting starts.

6. A timepiece including a chronograph mechanism, the chronograph mechanism comprising:

10 an energy accumulator comprised of a strip-spring;
 a regulating system;
 a gear train;
 a mechanism for winding the energy accumulator and resetting a minute counter to zero, arranged to wind the energy accumulator and reset the minute counter to zero at a same time; and
 a rack;
 wherein the rack has one end arranged to directly engage the strip-spring and another end arranged to directly engage with the gear train,
 wherein the rack is arranged to regulate a torque delivered by the strip-spring,
 wherein the rack is mounted to pivot in one direction of rotation to drive the gear train,
 wherein the rack connects the energy accumulator directly to the regulating system through the gear train driven by the rack, and
 wherein the mechanism for winding the energy accumulator and resetting a minute counter to zero includes at least one lever arranged to directly engage the one end of the rack.
